JOSEPH S. BARNUM, OF TOPEKA, KANSAS.

Letters Patent No. 88,602, dated April 6, 1869.

IMPROVED FASTENER FOR SECURING SPRINGS TO BED-BOTTOMS AND MATTRESSES.

The Schedule referred to in these Letters Patent and making part of the same.

Be it known that I, JOSEPH S. BARNUM, of the city of Topeka, and State of Kansas, have invented a new and useful Fastener, for locking spiral springs to the intersections of the steel strips in spring-mattresses, and, at the same time, for locking the strips at their intersection; and I do hereby declare that the following is a full, clear, and exact description of the construction and operation of the same, reference being had to the annexed drawings, making a part of this specification, in which—

Figure 1 is a perspective view of the device reversed, or upper side down, in order to show the "fastener" more plainly.

Figure 2, perspective view of the "fastener" A.

Figure 3, side view, or longitudinal elevation of the "fastener" A.

This device is for securing firmly together the strips of hoop-iron, at the intersections of these in making up a spring-mattress, and also of securing to the same place the spiral spring generally used for that purpose.

I construct the "fastener" of a single piece of metal, having four arms radiating from its centre, and two depressions, on its under side, crossing each other at right angles, *i i i i*, just wide enough to receive therein the intersection of two of the iron hoops, of which the mattress is composed, leaving at each corner, *c c c c*, a shoulder, *a a a a*, fitting into each of the four corners of the intersection of the hoops C C, D D.

These four shoulders form the end of the four arms of the "fastener" A. At two opposite angles, however, *b b*, the shoulders are extended so as to form a semi-cylindrical clamp, *c*, which receives the coil of the spring, the groove *c*, in said clamp, having its opening on the opposite side of the "fastener" to that side above described.

The "fastener" A is placed over the intersection of the hoops where it is required to affix a spring, the hoops being placed above the spring.

The cross-depressions in the "fastener" receive the "intersection" and the cylindrical clamp *b c*, showing its opening upward.

The smallest end of the spring is now passed beneath the hoops, and the end of the wire passed through the cylindrical clamp *c*, again under the hoop, into the other clamp *c*, thus making a firm lock together of the spring to the intersection.

A hole, or circular orifice in the centre of the "fastener" A, is for further securing the hoops to the same by means of the application of a punch to hoops over the hole, where a smart blow will drive that portion of the hoops over the hole into the hole, and form a further stay, or hold.

The larger end of the spring may be fastened to wooden or iron slats in the usual manner.

The advantage of this "fastener" is, that it is perfectly noiseless in its working, as it tightly locks the spring and the intersecting hoops, preventing any creaking at that point; also, its cheapness and readiness of appliance.

What I claim as my invention, and desire to secure by Letters Patent, is—

The "fastener" A, with its receptacles, *i i i i*, and shoulders, *a a a a*, and clamp, *b c*, and orifice, *d*, in its centre, as and for the purposes herein described.

JOSEPH S. BARNUM.
